UNITED STATES PATENT OFFICE.

JOHN H. BARNARD, OF BROOKLYN, NEW YORK, ASSIGNOR OF ONE-FOURTH TO HENRY NOBLE FLETCHER, OF ENGLEWOOD, NEW JERSEY.

INTERNAL-COMBUSTION ENGINE.

Application filed June 27, 1923. Serial No. 647,963.

To all whom it may concern:

Be it known that I, JOHN H. BARNARD, a citizen of the United States, and a resident of the borough of Brooklyn, city and State of New York, have invented certain new and useful Improvements in Internal-Combustion Engines, of which the following is a specification, reference being had to the accompanying drawings, forming part of this specification.

My present invention relates to improvements in internal combustion engines and, more particularly to internal combustion engines of the type in which the air necessary for the combustion of the fuel is compressed elsewhere than in the power cylinders, such as those illustrated and described in my co-pending applications Serial No. 600,184 of November 10th, 1922, and Serial No. 600,877 of November 14th, 1922.

In engines of this type the air necessary for the combustion of the fuel is compressed elsewhere than in the power cylinders, is admitted to the power cylinders during variable and controllable fractions of the power stroke through properly actuated admission valves and is impregnated immediately prior to such admissions with pulverized or finely divided fuel. The air with its content of fuel is received into combustion chambers forming part of, or communicable with, the power cylinders, where, together they impinge upon material sufficiently heated to start their chemical union and from whence they emerge into the power cylinders in a volume increased by the developed temperature of this chemical reaction.

An object of my present invention is to provide an improved and simplified means for effecting the mixing of the fuel and air and their admission into the power cylinder, and to provide an improved ignition means and combustion chamber.

Other objects of the invention are to provide means for supplying air of combustion and a fuel spray with an immediate direction co-axial with the admission valve for the fuel and air.

Other objects of the invention are to provide a combustion chamber in which a reversal of the direction of flow of the ignited mixture is caused in effecting its escape from the combustion chamber into the power cylinder; to provide an improved ignition means; and to provide a counter-flow dia-

phragm which permits the elimination of the "dummy" plug formerly devised for ignition during steady operation.

With these and other objects, which will be perceived from the following description, the invention comprises, the apparatus described and set forth in the following specification and claims.

The various features of the invention are illustrated in the accompanying drawings, in which;

Fig. 1 is a sectional view of a portion of a power cylinder and of a fuel and air supply means therefor embodying a form of my invention, the invention being illustrated as applied to apparatus of the same general construction as shown in my co-pending application Serial No. 600,877, portions of the apparatus being illustrated diagrammatically and utilizing the spraying device illustrated therein, but more particularly covered in my co-pending application, Serial No. 375,830, filed April 22nd, 1920.

Fig. 2 is a cross section of the admission valve within a cage which forms the means of its assemblage with the head of the power cylinder in which it is installed on the line $x-x$ of Fig. 1, with the spray nozzle omitted.

Fig. 3 is a perspective view of the admission valve and its valve stem, shown removed from its cage.

Fig. 4 is a vertical longitudinal section of the spray nozzle.

Fig. 5 is a vertical longitudinal section of a typical form of counter-flow diaphragm adapted to act as a baffling communication between the combustion chamber and the power cylinder.

Fig. 6 is a plan view of the electric igniter surrounding the nozzle of the counter-flow diaphragm.

In my present invention a supply of air under pressure is passed through an inlet valve, preferably of conical shape, into a combustion chamber which communicates with the power cylinder and, before entering the power cylinder is caused to reverse its direction of travel. Fuel is sprayed into the air stream, as it approaches the inlet valve, in a direction substantially the same as the movement of the air and, as the direction of movement of the air stream is reversed, a thorough agitation and mixing of the fuel and air is obtained. The air and

fuel mixture is ignited at the place of the reversal of its movement by means of a glowing wire or equivalent ignition means. The stream of air and fuel is preferably 5 given a flaring conical path of travel by the cone shaped valve and is received in an annular combustion chamber the outer portion of which is parallel with the air flowing over the surface of the valve and is turned 10 inwardly at the base of the combustion chamber to pass over a conical shaped partition and through a central opening to the power cylinder.

Referring more particularly to the various figures of the accompanying drawings, but principally to Fig. 1, 1 represents a part of the casting forming the head of one of the power cylinders of an internal combustion engine of the described type, 2, 15 water spaces in this head, 3, water spaces in the walls 4 of the power cylinders, such as 5. Formed within the cylinder head is the mixing chamber 6 which is continuously filled with compressed air through the passage 7 by which it is connected with a constantly supplied receiver. Neither receiver nor its source of supply are shown herein as they are in no wise peculiar to this invention and are fully described in my above 20 named co-pending applications.

Set into the cylinder head is the admission valve cage 8, fitted closely upon the seat 9. This cage is secured in place by the locking ring 10 which is sealed by the 35 gasket 11. Through the wall of this cage is the aperture 12 affording unrestricted communication between the space 6 and the interior of the cage which, consequently, forms part of the mixing chamber. An extension 13 of this cage fills the double purpose of forming the lower tray of the spiral spring 14 and a guide for the stem of the admission valve now to be described.

For assemblage purposes, the valve itself 40 consists of the upper cone 15 and the detachable lower cone frustum 16, unitable by any suitable means, such as the stud 17, which is preferably screwthreaded as shown. This upper cone 15 is carried by 45 the radial bars 18 which are extended upward until they unite in the disc 19 slidably fitted in the cage 8, above the aperture 12. Beyond this disc 19 extends the valve stem proper 20. This carries the piston 21 fitted 50 with the piston ring 22 sliding in the chamber 25 which is recessed in the extension 13. Above this piston ring there is no attempt 55 to seal the chamber 25 or, indeed, a vent hole may be provided to allow the escape of such small leakages as may occur past the 60 piston ring, so that, this upper part of the chamber 25 is always at atmospheric pressure as is the condition below the admission valve, except during the power stroke. In 65 consequence, if the area of the piston 21 is

made equal to the surface of the admission valve exposed to mixing chamber pressure the spring 14 is relieved of the necessity of overcoming the mixing chamber pressure in holding the admission valve closed.

In the valve stem 20 there is cut the slot 23 into which there projects the guide pin 24 to preclude any possibility of rotational movement by the valve parts which might cause the bars 18 changing their positions 70 with reference to the aperture 12.

Above the extension 13, the valve stem 20 carries the upper tray 26 which holds the spring 14 in compression causing it to maintain the admission valve closed against its seat 27. The admission valve is suitably opened by the pressure of a timed rocker-arm upon the head 28 of the valve stem 20. This arm and the means of its actuation are not shown since they are fully described 75 in my co-pending application Serial No. 600,877.

Located co-axially with the admission valve, and with the admission valve cage, is the spray nozzle 29, shown in more detail 80 in Fig. 5. The principles of the means employed by me for the pulverization of the fuel are fully set forth in my co-pending application Serial No. 375,839 on fuel spraying devices, hence, for the purposes 85 of this application, the following description of these means should suffice.

There is diagrammatically shown as 90 an air pump driven by such properly timed mechanism as is shown in my co-pending 100 application Serial No. 600,877. This draws in hot, compressed air from the mixing chamber 6, through the suction pipe 33 and expels it through the pipe 30 into the chamber 36 of the nozzle 29. There is also dia- 105 grammatically shown as 34 an oil pump similarly actuated drawing its supply through the suction pipe 35 from a source of supply which is not shown. For reasons set forth in the previously mentioned applica- 110 tion the delivery stroke of the air pump begins slightly in advance of that of the fuel pump though they terminate together.

The discharge from the fuel pump is ex- 115 pelled through the pipe 31 and the small orifice 40 into the chamber 38 of the nozzle 29. There, it is met by the cross blast of air through the small orifice 37 affording communication between the chambers 36 and 38. From chamber 38, the mingled oil and air escape through the orifice 41 as a spray into the re-pulverizing chamber 39 whence they are discharged in a still more divided state, by the orifice 42, in a cone substantial- 120 ly similar to the surface of the admission valve. The timing of the emission of this spray is nearly coincident with the begin- 125 ning of the opening of the admission valve being just enough subsequent thereto to insure the begining of a rush of air past the 130

valve into which the first of the spray is caught.

Beyond the admission valve there is located the combustion chamber 43 separated 5 from the power cylinder 5 by the diaphragm 44 except for the aperture 45 in the central nozzle 46. The exterior and interior walls of this combustion chamber are conical and conform in a general way with the cone of 10 air and fuel spray issuing from the admission valve.

Well down, in this combustion chamber, there is located the ring 47 composed of material offering considerable electrical resistance, capable of standing recurring periods 15 of high temperature and not too deleteriously affected by a hydro-carbon atmosphere. Compositions suitable to the purposes of 20 this ring are disclosed in my co-pending application on ignition devices Serial No. 499, 681.

This ring is supported by the two clamps 48 and 49 of which the former is grounded upon the body of the engine and the latter 25 is insulated therefrom by the refractory and non-conducting bushing 50.

Into the clamp 49 there is conveyed, by the conductor 51 and the wire 52, an electric current from any convenient source of supply, such as a low voltage generator, not 30 shown. The conductor 51 is sealed and insulated at its entrance into the cylinder head by the insulating packing gland 53 and 54.

Prior to starting the engine the temperature 35 of the ring 47 is raised, by a flow of current, to a bright glow. Upon the beginning of each opening of the admission valve the first of the charge of air and fuel is ignited by contact with this glowing ring. 40 Bursting into flame, and multiplied in volume by its rise in temperature, it can only escape into the power cylinder by rising over the lip of the nozzle 46 and through the aperture 45 while into this baffled flame 45 the balance of each charge pours from the admission valve.

For the purpose of limiting the use of electric ignition to periods of starting and for working the engine intermittently, I 50 cause the material of the diaphragm to become heated by the effects of successive combustions by inserting the refractory and low conducting rings 55 and 56 by which the flow of heat from the diaphragm is retarded. These insulating rings and the diaphragm are secured in position by the locking ring 57.

In order for the mechanism as above described to be clearly understood in connection with the internal combustion engine of my prior application No. 600,877, it should 55 be stated that the air pump 32, above referred to, is referred to in my prior application by the reference numerals 95 and 96, 60 and that the oil pump 34 is therein re-

ferred to by the numerals 119 and 120. The passage 7 to the mixing chamber 6 leads 65 from the tank 38 in the said early application No. 600,877, and the mixing chamber 6 herein is indicated by the numeral 43. 70 The combustion chamber 43 herein is indicated in the prior application by the numerals 47 and 48, the compression spring 14 herein being the same as the compression spring 56 in said early application. 75

As changes of construction could be made within the scope of my invention it is intended that all matter contained in the above description or shown in the accompanying drawings be interpreted as illustrative and not in a limiting sense. 80

Having described my invention I claim as new and desire to secure by Letters Patent:

1. An internal combustion engine which comprises a power cylinder, a combustion chamber therefor, external means for compressing air for combustion and supplying said air to the combustion chamber, a valve for controlling the admission of this air to said combustion chamber, means for spraying liquid fuel into said air in hollow conical form as they enter said combustion chamber. 85

2. An internal combustion engine, a power cylinder, a combustion chamber therefor, external means for compressing air for combustion and supplying said air to said combustion chamber, a valve for admitting said air to said combustion chamber during fractions of the power stroke, and means for impregnating the air as it enters said combustion chamber with finely pulverized liquid fuel sprayed co-incidently with the entering air in hollow conical form. 90

3. An internal combustion engine having a power cylinder, external means for compressing air for combustion and supplying said air to said power cylinder, a valve for controlling the admission of said air to the power cylinder, means for spraying liquid fuel into said air, and a baffle so fashioned 100 and positioned as to form a vaporizing and ignition chamber for said fuel and air admitted through said valve to cause said fuel and air to reverse and bring the ignited mixture in contact with the entering fuel and air. 105

4. An internal combustion engine having a power cylinder, means for compressing air and supplying said air to said power cylinder, a valve for controlling the admission 110 of air to said power cylinder and means for impregnating said air with fuel, an ignition device in the path of the air and fuel passing through said valve, a baffle so fashioned and positioned as to cause said admitted air and fuel to reverse their direction of movement and bring said ignited mixture in contact with the incoming air and fuel. 115

5. An internal combustion engine, power 120

125

130

4
cylinders, a valve for admitting air and fuel for combustion to each of the power cylinders respectively during progress of the power stroke, an ignition device in the path 5 of said entering air and fuel, and a baffle so fashioned and positioned as to arrest and cause the reversal of direction of movement of said air and fuel about said ignition device, said baffle being heat-insulated to attain and retain a temperature of ignition 10 at said place of reversal.

6. An internal combustion engine in which the air and fuel of combustion are delivered through an admission valve during 15 progress of the power stroke, an ignition means for said air and fuel passing said valve, and a baffle so fashioned and positioned as to cause the flame resulting from the ignition of said fuel and air to reverse 20 and come in contact with succeeding portions of the charge.

7. An internal combustion engine in which the air and fuel for combustion are delivered into the power cylinders during the 25 progress of the power stroke, means for arresting and reversing the earlier portions of the admitted air and fuel, and means for bringing said reversed and ignited earlier portions into heat interchanging relations 30 with the later portions of the air and fuel charged.

8. An internal combustion engine, in which the air and fuel for combustion are delivered together into the power cylinders 35 during the progress of the power stroke, at a velocity greater than that of the propagation of flame therein, means for igniting said mixture of air and fuel and means for bringing said ignited portions into contact 40 with succeeding portions to ignite said succeeding portions.

9. An internal combustion engine in which a charge of air and fuel for combustion is delivered at a velocity greater than that of 45 flame propagation therein during the progress of the power stroke, means for arresting the flow of the earlier portions of said charge and igniting said arrested portions and then directing said ignited earlier portions of the charge into direct contact with 50 succeeding portions to ignite said succeeding portions by said contact.

10. Apparatus of the type described which comprises, a power cylinder, a valve for said 55 cylinder, means for supplying air through said valve, a combustion chamber between said valve and said power cylinder and a fuel spray in axial alignment with and in advance of said valve.

60 11. Apparatus of the type described which comprises, a power cylinder, a valve for said cylinder, means for supplying air through said valve, a combustion chamber between said valve and said power cylinder and a fuel spray in axial alignment with 65

said valve, said valve and said combustion chamber being arranged to cause a reversal of the direction of movement of said air and fuel.

12. Apparatus of the type described 70 which comprises, a power cylinder, a valve for said cylinder, means for supplying air through said valve, a combustion chamber between said valve and said power cylinder, a fuel spray in axial alignment with said valve, said combustion chamber being arranged to cause a reversal of movement of said air and fuel from said valve, and an ignition device at the place of reversal of 75 said air and fuel mixture.

13. Apparatus of the type described which comprises, a power cylinder, a valve for said cylinder, means for supplying air through said valve, a combustion chamber between said valve and said power cylinder, a fuel spray in axial alignment with said valve, said combustion chamber being arranged to cause said air and fuel to move in a diverging cone shaped path and to reverse its direction of travel and pass inwardly through 85 a central opening to said power cylinder.

14. Apparatus of the type described which comprises, a power cylinder, a cone shaped inlet valve for said power cylinder, a fuel spray device directed axially toward the 90 apex of said valve, an annular frusto-conical combustion chamber between said valve and said power cylinder and aligned with the surface of said valve, said combustion chamber having a central opening to said 95 power cylinder, and an ignition device at the base of said combustion chamber.

15. Apparatus of the type described which comprises, a power cylinder, a conical inlet valve to said cylinder, a valve chamber therefor, means for supplying air to said valve chamber, a fuel spray in said valve chamber axial with and directed towards the apex of said valve, an annular combustion chamber between said valve and said power cylinder and a frusto-conical partition between 100 said combustion chamber and said cylinder and projecting into said combustion chamber.

16. Apparatus of the type described which 105 comprises, a power cylinder, a conical inlet valve therefor, a fuel spray axial with and directed towards the apex of said valve, and a frusto-conical partition between said 110 valve and said cylinder forming an annular combustion chamber therebetween.

17. Apparatus of the type described which 115 comprises, a power cylinder, a conical inlet valve therefor, a fuel spray axial with and directed towards the apex of said valve, a frusto-conical partition between said valve and said cylinder forming an annular combustion chamber therebetween, and an annular ignition device in said combustion 120 chamber.

18. Apparatus of the type described which comprises, a power cylinder, a conical valve therefor having a number of supporting and actuating rods parallel with the axis of said

5 valve and a fuel spray axial with and directed towards the apex of said valve.

19. An internal combustion engine which comprises power cylinders and pistons, means for compressing and supplying air to

10 said power cylinders, means for spraying

fuel into said air in direct proportion to the quantity of said air, means for directing said air and sprayed fuel in a conically diverging path, means of ignition in the path of said air and sprayed fuel, and means for redirecting the products of combustion in a 15 conically converging path in opposition to any and all continuing flow of air and fuel.

JOHN H. BARNARD.
